UNITED STATES PATENT OFFICE.

FREDERICK C. HOLTZ, OF SPRINGFIELD, ILLINOIS, ASSIGNOR TO SANGAMO ELECTRIC COMPANY, OF SPRINGFIELD, ILLINOIS, A CORPORATION OF ILLINOIS.

POLARIZED RELAY.

Application filed August 30, 1924. Serial No. 735,179.

Some types of polarized relays operate upon the principle that current of one sign established in an electrical circuit which includes the relay causes a movable member thereof to operate in one direction, while a reversal in sign of the current flow causes such member to move in the reverse direction. Other types of polarized relays comprise rotatable members arranged to make 10 a portion of a complete revolution in a given direction for each reversal in sign of the current flow. Both types have heretofore been limited to the use of direct current, and the object of my invention is to provide an 15 improved construction by which relays of either of the above mentioned types may be adapted for use in either direct or alternating current circuits. This object I accomplish as 20 illustrated in the drawings and as hereinafter described. What I regard as new is set forth in the claims.

In the drawings,—

Fig. 1 is a diagrammatic view showing my improvements embodied in a polarized 25 relay of the rocking or oscillating type, together with its electrical connections;

Fig. 2 is a side elevation of the principal parts shown in Fig. 1;

Figs. 3 and 4 are diagrams explanatory of 30 the operation of my improved relay;

Fig. 5 is a perspective view illustrating my improvements embodied in a polarized 35 relay of the rotating type, with an indicator associated therewith; and

Fig. 6 is a diagrammatic view showing the construction of the relay illustrated in Fig. 5.

Referring first to the structure shown in Figs. 1 and 2, 6 indicates the core of an 40 electromagnet composed of a plurality of C-shaped laminations 7 riveted together forming an upper or vertical pole 8, and a lower or horizontal pole 9. The latter pole is provided with a cross-bar 10 at its extremity, and secured to said cross-bar, preferably by set screws 11, is a U-shaped core 45 12 having upwardly extending poles 13, 14 equally distant from and at opposite sides of the pole 8, but lying in the same transverse vertical plane therewith, as shown in Fig. 2. By this arrangement the tip 15 of the pole 8 is placed midway between the tips

16, 17 of the poles 13, 14 and separated therefrom by an air gap 18.

Mounted on the pole tip 15 by means of 55 a small bracket 19 secured thereto in any suitable way, is a soft iron armature 20 in the form of a flat bar pivotally mounted between its ends on a pivot 21 supported by said bracket. As best shown in Fig. 1, the 60 ends of the armature 20 extend over the ends of the pole tips 16, 17, so that by the rocking of said armature either end thereof may move into contact with the underlying pole tip 16 or 17, as the case may be. In the 65 opposite end portions of said armature are mounted small brass pins 22, 23 which are adapted to strike the pole tips 16, 17, respectively, to keep the armature itself from coming into direct contact with said pole 70 tips.

Mounted on the pole 8 in any suitable way is a coil 24, the terminals 25, 26 of which are connected to wires 27, 28 representing an 75 alternating current supply.

On the poles 13, 14 are mounted coils 29, 30, preferably composed of a large number of turns, and so arranged that their magnetic effects relative to the laminations of the core 12 are cumulative, that is to say, 80 for a given direction of current flow through these coils the fluxes thereof both flow in the same direction in the core. The terminals 31, 32 of the coils 29, 30 are suitably arranged to be connected to the alternating 85 current supply 27, 28 through a reversing switch 33, shown diagrammatically in Fig. 1, so that their sign of connection may be reversed as desired. It will be understood, of course, that instead of the reversing 90 switch any other suitable arrangement for reversal may be employed.

The electrical circuits of the coil 24 and the coils 29, 30 are so arranged that when both circuits are connected to the supply wires 27, 28 the instantaneous value of current in each circuit is either in phase or in phase opposition, depending upon the position of the reversing switch. Referring now to Fig. 3, the ordinates of the curve A represent the 10 instantaneous values of the magnetic flux resulting from the current established in the coil 24. With the armature 20 held in its neutral position, shown in Fig. 1, it

should be clear that this magnetic flux divides in such a way that a part of it passes along the armature 20 toward the pole tip 17, while the remainder enters the laminations of the core 12 by way of the pole tip 16. With current established in the windings 29, 30, as already stated, the instantaneous flux in the gap 18 and the armature 20 due to these coils may be shown by the 10 curve B in Fig. 3. The interaction of these two fluxes will cause a considerable weakening in the total flux at one end of the armature 20, and a corresponding increase in that at the other end thereof, with the result 15 that the armature will tend at once to pull down at the end showing an increase in the flux. When the instantaneous flux values from both currents are both positive or both negative, the armature 20 will remain stationary with one or the other of its extremities in contact with one or the other of the pole tips 16 or 17, and this position will not be disturbed by momentary interruptions of the current flowing through the coils 29, 30. 20 A reversal in the position of the reversing switch 33, however, reverses the sign of the current flowing through said coils with reference to the current flowing through the coil 24, and as a result the magnetic flux 25 in the laminations of the core 12 reverses its direction, as indicated by the dotted line C in Fig. 3. This reversal causes the armature 20 to rock so as to assume a reversed position, which it will maintain so long as the 30 sign of the current is not again changed. The device, therefore, constitutes a polarized relay, or a polarity indicator, and can be used as a counting device by suitably connecting the armature 20 to a proper gear 35 mechanism so that each reversal of the reversing switch will step the counting mechanism forward by one unit. The same arrangement may also be used as a cycle counter or electrical timer by suitably altering the constants of the electrical circuits of the coil 24 so that the instantaneous value of current is in quadrature with the current flow in coils 29, 30. The mode of operation 40 under this assumption is shown in Fig. 4, in which curves A' and B' indicate the instantaneous values of the flux in each of the magnetic circuits. For each condition 45 where the instantaneous values of flux are in the same direction, the armature 20 takes up one position, while for values of reversed sign the armature takes the reversed position. From the illustration in said figure it 50 will be noted that the reversal takes place at twice the frequency of the supply, that is, there is one complete reversal for each 55 half cycle.

It will be understood that my invention is not limited in its application to the arrangement above described, and by way of 60 example, in Figs. 5 and 6 I have illustrated

another embodiment thereof in which a 70 Z-shaped armature 34 is mounted on a shaft 35 to rotate directly in front of two soft iron pole pieces 36, 37 which are connected respectively to soft iron cores 38, 39. Said cores carry two windings consisting of two 75 sets of coils 40, 41 and 42, 43, respectively. The coils 40, 41 of one set are connected in series to the source of supply of current, and their sense of winding is such as to create at the tips of the pole pieces 36, 37 80 poles of like polarity, the magnetic circuit for each being completed through the Z-shaped armature 34, the shaft 35 thereof, and a soft iron pole piece 44 in which one end of said shaft is journaled. The alternating current traversing the winding 40-41 may be regarded as the polarizing current for the device. It will be understood 85 that the pole piece 44 is connected to the cores 38, 39. In the illustration of Fig. 90 5 the armature shaft 35 is shown as being provided with a worm 45 which drives a worm wheel 46 mounted on a shaft 47 that carries a pointer 48 operating over a dial 49 provided with a scale 50. This arrangement is shown merely as an illustration of one way in which the device may be connected up for use as an indicator. As shown in Fig. 6, the coils 42, 43 are connected in series, and are wound in a reverse 95 sense so that they tend to create at the tips of the pole pieces 36, 37 poles of opposite polarity. These coils are connected to the same source of supply as the coils 40, 41, and carry current of the same frequency 100 and phase, which latter current may be regarded as the operating current of the device. Under such conditions the magnetic flux from the poles 36, 37 is always unbalanced, and there is a strong tendency to 105 hold the armature 34 in a fixed position, somewhat as shown in Fig. 5. Upon reversing the sign of the operating current in the coils 42, 43 the armature is carried a quarter revolution in a counter-clockwise 110 direction as viewed in Fig. 5. It will be 115 clear that for each reversal of current in the coils 42, 43 the armature will make one quarter revolution in the direction indicated.

While both forms of the apparatus described are similar in structure to those used in direct current circuits, there remains one fundamental difference. Alternating current magnetomotive forces replace the usual permanent magnet, and alternating current is used in the windings ordinarily supplied with direct current. Such devices operate as polarized relays when the currents in the two sets of windings are in phase or in 120 phase opposition, and as cycle counters when the same currents are adjusted to be in quadrature. The same devices will 125 operate as polarized relays from a direct cur-

rent source of supply, this being merely a special case of the alternating current.

What I claim as my invention and desire to secure by Letters Patent, is—

5 1. A relay comprising a movable member, and two electrical circuits and associated magnetic circuits, including pole pieces operatively disposed relatively to said movable member, each of said electrical circuits being 10 traversed by only one alternating current, the individual currents of both circuits being of the same frequency and of such relative phase that upon each reversal of sign of the current flow in one of said electrical circuits said movable member is actuated.

2. A relay comprising a movable member, two electrical circuits and associated magnetic circuits, including pole pieces operatively disposed relatively to said movable member, each of said electrical circuits being 20 traversed by only one alternating current, the individual currents of both circuits being of the same frequency and of such relative phase that upon each reversal of sign of the current flow in one of said electrical circuits said movable member is actuated, and means for reversing the current flow in one 25 of said electrical circuits independently of the other.

3. A relay comprising a movable member, and two electrical circuits and associated magnetic circuits, including pole pieces operatively disposed relatively to said movable member, each of said electrical circuits being 35 traversed solely by a single alternating current, the individual currents of both circuits being of the same frequency and of substantially the same phase so that for one 40 direction of current flow in said electrical circuits said movable member takes up one position, while on reversal of the flow of current in one of said electrical circuits said movable member takes up a different 45 position.

4. In a device of the class described, the combination of a magnet structure, alternating current circuit connections for an operating current and a polarizing current, 50 separate windings on said magnet structure, each traversed by only one of said currents, and a movable member responsive to the flux in said magnet structure, said operating and polarizing currents being of the same 55 frequency and of such relative phase that upon each reversal of sign of said operating current said movable member is actuated.

5. In a device of the class described, the combination of a magnet structure, two 60 windings on said magnet structure traversed by individual alternating currents, and a rotating armature responsive to the flux in said magnet structure, said currents being of the same frequency and of such relative

phase that upon each reversal of sign of the 65 current flow in one of said windings said rotatable armature is actuated.

6. In a device of the class described, the combination of a magnet structure comprising a pair of cores, poles on said cores, two 70 windings on said cores traversed respectively by alternating currents of the same frequency, and a rotating armature disposed in proximity to said poles and adapted to be actuated upon each reversal of sign of the 75 current flow in one of said windings.

7. In a device of the class described, the combination of a magnet structure comprising a pair of cores magnetically connected together at one end, poles at the other ends 80 of said cores, two windings on said cores each traversed by an individual alternating current, a rotating armature disposed in proximity to said poles, said alternating currents being of the same frequency and of 85 such relative phase that upon each reversal of sign of the current flow in one of said windings said armature is actuated, and means for reversing the current flow in one 90 of said windings independently of the other. 90

8. In a device of the class described, the combination of a magnet structure comprising two cores magnetically connected together at one end, poles at the other ends of 95 said cores, two windings on said cores traversed by alternating currents of the same frequency, a rotating armature disposed in proximity to said poles and adapted to be actuated upon each reversal of sign of the current flow in one of said windings, and 100 a shaft on which the armature is mounted, said armature and shaft forming a part of the magnetic circuit of said cores.

9. In a relay of the class described, the combination of a pair of cores, a supporting 105 member magnetically connecting said cores together at one end, poles at the other ends of said cores, two windings on said cores traversed respectively by individual alternating currents, a shaft rotatably supported 110 by said supporting member, and an armature mounted on said shaft in proximity to said poles, said alternating currents being of the same frequency and of such relative phase that upon each reversal of sign of the current flow in one of said windings said armature is rotatively advanced. 115

10. In a device of the class described, the combination of a magnet structure comprising a pair of poles, two windings on said 120 magnet structure traversed by two alternating currents, and a rotating armature of approximately Z shape disposed in proximity to said poles and adapted to be rotatively advanced upon each reversal of 125 sign of the current flow in one of said windings.

FREDERICK C. HOLTZ.
